ATTORNEY

UNITED STATES PATENT OFFICE

161,207

COMBINATION TRANSPARENT FISH BOWL AND HANDLE

Earl A. Rice, Mercersburg, Pa.

Application September 26, 1949, Serial No. 5,175

Term of patent 14 years

(Cl. D91—2)

To all whom it may concern:

Be it known that I, Earl A. Rice, a citizen of the United States, residing at Mercersburg, in the State of Pennsylvania, have invented a new, original, and ornamental Design for a Combination Transparent Fish Bowl and Handle, of which the following is a specification, reference being had to the accompanying drawing, forming a part thereof.

In the drawing:

Fig. 1 is a perspective view of a combination transparent fish bowl and handle showing my new design.

Fig. 2 is a top plan view thereof.

Fig. 3 is a side elevational view thereof.

I claim:

The ornamental design for a combination transparent fish bowl and handle, as shown.

EARL A. RICE.
